BUCKLE LOCKS FOR LUGGAGE OR THE LIKE

Charles S. Gehrie, Montclair, N.J., assignor to Presto Lock Co., Inc., Garfield, N.J., a corporation of New York

Filed Mar. 3, 1966, Ser. No. 1,280

Term of patent 14 years
(Cl. D50—7)

FIG. 1

FIG. 2

FIG. 3

FIG. 4

FIG. 5

FIG. 1 is a top plan view of buckle locks for luggage or the like embodying my new design;

FIG. 2 is an elevational view taken from the bottom of FIG. 1, the view from the top of FIG. 1 being a mirror image thereof;

FIG. 3 is an end elevational view as seen from the left of FIG. 1;

FIG. 4 is an end elevational view as seen from the right of FIG. 1; and

FIG. 5 is a bottom plan view.

The essential features of my design reside in the full line showing thereof.

I claim:

The ornamental design for buckle locks for luggage or the like, as shown and described.
